DESIGN FOR A COMBINED PICTURE FRAME AND EASEL SUPPORT

Willy Katz, Woodside, N. Y.

Application September 24, 1942, Serial No. 108,327

Term of patent 7 years

To all whom it may concern:

Be it known that I, Willy Katz, a citizen of the United States, residing at Woodside, in the county of Queens and State of New York, have invented a new, original, and ornamental Design for a Combined Picture Frame and Easel Support, of which the following is a specification, reference being had to the accompanying drawing, forming part thereof.

Fig. 1 is a front elevational view of a combined picture frame and easel support showing my new design;

Fig. 2 is a rear elevational view thereof, and Fig. 3 is a side elevational view.

The essential features of my design reside in the annular band member framing the photograph receiving opening in association with the contrasting color diagonal bands and the bird in flight, all as shown best in Fig. 1 of the drawing.

I claim:

The ornamental design for a combined picture frame and easel support, as shown and described.

WILLY KATZ.
